OUTDOOR STANDARD

Ingvald Hanson, Willmar, Minn., assignor of one-fourth to Gewaine H. Hanson, one-fourth to Nels P. W. Jensen, and one-fourth to Archie Caylor, Willmar, Minn.

Application June 26, 1953, Serial No. 364,407

2 Claims. (Cl. 189—23)

This invention relates to an outdoor standard and more particularly to an easily mountable and adjustable standard for such use as a television antenna tower.

I am aware of certain prior art standards such as that disclosed in United States Patent Number 1,102,413 issued to N. A. Jensen, on July 7, 1914, which disclosed a standard comprising a pole pivotally mounted on a rigid support for swinging to upright position in abutting relation with the support with which it is then secured.

Other prior art references disclosed various standard devices swingably mounted to a rigid support. Further, there are television antenna mounts in which the antenna tuning network can be rotated to a desired position best suited for receiving television signals from a specific source.

To the best of my knowledge, there is no standard other than that disclosed in this specification which has means for raising and securing an elongated pole in vertical position and at the same time providing for rotatable adjustment of the standard.

It is therefore a general object of this invention to provide an elongated outdoor standard pivotally secured near its lower end to a rigid support and which can be raised to vertical position and oriented to any direction of the compass.

Another object of the invention is to provide a television antenna tower, the lower end portion of which is pivotally mounted to a rigid support and which can be raised to vertical position by winch mechanism, the pole being rotatable either before or after raising to any desired directional position.

It is a still further object to provide a device of the class described which will be economical both in construction and operation and which has structural strength necessary for such purposes as a flag pole or as a television antenna tower yet being capable of manipulation so that the device may be quickly lowered in the event of a storm or when it is desired to repair the device.

These and other objects and advantages of my invention will more fully appear from the following description made in connection with the accompanying drawings wherein like reference characters refer to similar parts throughout the several views and in which:

Fig. 1 is a front elevation of my standard with the base member shown in vertical section. The standard in extended horizontal position is shown in dotted line while the retracted vertical position is shown in full line;

Fig. 2 is an enlarged segmental side elevational view of the lower portion of my standard taken on the line 2—2 of Fig. 1; and

Fig. 3 is a horizontal section of the winch and cradle mechanism taken on the line 3—3 of Fig. 1.

Referring now more particularly to the drawing, Fig. 1 shows an upstanding rigid support such as the steel pipe 10 which is secured in a base such as the concrete form 11 within ground 12. The upstanding support 10 is intended to be rigidly and permanently secured to the base 11 and to be of the requisite structural strength

to hold the remaining portions of the standard in secure upstanding relation.

Secured to the upstanding support 10 is mounting means M which mounting means is adjustably rotatable on said support and, in the form shown, comprises first a mounting pin 13 which extends downwardly and concentrically within the cylindrical portion of upstanding pipe 10 as shown. The mounting pin has an offset yoke portion 14 and a downwardly extending shaft 15 with a flange 16 medially disposed between the yoke 14 and the shaft 15. A flange 16 is adapted to abut against the collar 17 which is rigidly secured to the top of the upstanding support 10. Securing means such as the set screw 18 is threadably secured to the collar 17 so as to be engageable with the mounting pin 13 and to hold it in adjustably rotated position with respect to the support member 10. The other portion of the mounting means M comprises a retractile and extensible mechanism 19 rotatably and adjustably secured to a lower part of the rigid support 10 as shown. Collars 20 and 21 are secured to the support 10 and prevent endwise movement of the retractile and extensible mechanism 19 while allowing rotatable movement about the support member 10. A retractile and extensible mechanism 19 preferably comprises an annular cylinder portion 22 to which tangential side plates 23 and 24 are secured as shown in Fig. 3. The outer ends of the plates 23 are flared as at 25 and 26 so as to present an entranceway for cradling the lower end of the standard as will be presently described. Immediately beneath the flared end portions 25 and 26 is mounted a winch 27 which in turn comprises a shaft 28 journaled across the plates 23 and 24 and having means at the outer end such as nut 29 threadably secured thereto and a handle member 30 rigidly secured to the other end. Medially of the shaft 28 and interposed between the plates 23 and 24 is a spool 31, the spool being supplied with a coiled length of cable 32. Ratchet means 33 may be employed to prevent accidental reverse movement of the winch mechanism 27 when the cable 32 is being wound or retracted on said spool 31. The ratchet mechanism may constitute an ordinary toothed periphery 34 formed at one side of spool 31 which cooperates with a latch or dog 35 having a pivotal mounting within the plate 24 and bearing a manual handle 36 at the outer side thereof. The entire retractile and extensible mechanism may be secured in its rotated and adjusted position by such means as set screw 37 shown in Figs. 1 and 3.

Pivoted secured to the mounting means, and more particularly to the laterally extending yoke 14, is an elongated pole P, the pivotal point being indicated at 14a. The pole P is pivoted intermediate its upper and lower end in such a manner that the upper portion 38 is considerably longer than the lower extending portion 39 as shown in Fig. 1. The pole P may be conveniently constructed of lengths of tubular structural material, each length being successively of lesser diameter in an upward direction toward the top end of the pole. The joints may be formed as by threadable connections 40 extending from the bottom to the top. Additional bracing for the pole may be supplied by strut members 41 secured as shown in Fig. 1 and braced medially by a strut support 42 as shown. At the extreme upper end of pole P an antenna network 43 may be secured although it is understood that the standard may be used for other purposes such as for an adjustable flag pole.

In the use and operation of my device, the upstanding rigid support 10 is firmly secured with respect to the ground in such media as a concrete base 11. The pole P is then pivotally mounted to the yoke 14 with the pole being in unraised position as shown by dotted lines in Fig. 1. Cable 32 is then coiled about the spool 31 and the

free end thereof is attached to the lower end 10 of the pole P as shown. The handle 30 of the winch 27 is then rotated in a clockwise direction as viewed in Fig. 1 so as to retract the cable 32 and move downwardly the lower extending end 39 of the pole P. Since the upper longer extension 38 is in alignment with the arm 39, the entire pole P will be raised to a vertical position as shown in full line in Fig. 1. The bottom end of the lower extremity 39 will then enter between the flared ends 25-26 which constitute the cradle portion of the retractile and extensile mechanism 19 and the lower end 39 of pole P will then be in abutting relation with the side of the support member 10. A pin 44 is then inserted through aligned openings in plates 23, 24 and the lower end of the pole P as shown in Figs. 1 and 2.

The pole P as now secured in firm abutting relation with the upstanding rigid support 10 and the set screws 18 and 37 may then be loosened so as to rotate the entire pole P together with the mounting means M to the required directional orientation. In the case where the standard is used as a television antenna tower, the tuning network 43 of the antenna may be supplementally oriented until the desired reception is acquired. At this rotatably adjusted position, the set screws 18 and 37 are secured so as to maintain the pole P in upstanding secured relation with respect to the support member 10.

When it is desired to again rotate the pole or to lower the device as in the case of storm conditions or for repairing the device, the winch mechanism 27 can be utilized to lower the pole to the horizontal position shown in Fig. 1. The pin 44 is first withdrawn, then the cable 32 is permitted to extend while depressing the manual handle member 36 to disengage the latch or dog 35 from the ratchet teeth 34. When the pole has reached the horizontal position, it may be left temporarily until it is again desired to raise the pole.

It may thus be seen that I have devised an extremely economical and versatile standard or tower of sufficient height and structural property to accommodate a television

antenna, yet which can be mounted, dismounted, or adjusted by one or two men with ease.

It will, of course, be understood that various changes may be made in the form, details, arrangement and proportions of the parts without departing from the scope of my invention.

What I claim is:

1. A standard adapted for use as a television antenna tower and the like comprising, an upstanding longitudinal support rigidly securable at its lower end to the ground, a yoke secured in rotatable adjustment on a vertical axis at the upper portion of said support, said yoke having a horizontal pivot pin laterally off-set from the longitudinal upward projection of the support, an elongated pole having an upper and a lower end, said pole being pivotally mounted relatively closer to the lower end thereof on said horizontal pivot pin, and a winch mechanism mounted in off-set relation on the lower portion of the support and secured against vertical shifting relative thereto and rotatably adjustable about the axis of said support, said winch having side plates flared outwardly of the support for cradling said pole in rigid parallel relation with the support and further having extensible connection with the lower end of said pole to permit the pole to pivot from upstanding rigid contact with the flared side plates to a lowered position lateral to the axis of said support.
2. The subject matter set forth in claim 1 and a pair of abutment collars secured to said support for bearing engagement with the winch mechanism.
